UNITED STATES PATENT OFFICE.

PHILIPP REINER, OF COLOGNE, PRUSSIA, GERMANY, ASSIGNOR TO JOHN H. VOLKMANN, OF NEW YORK, N. Y.

VENDING APPARATUS.

SPECIFICATION forming part of Letters Patent No. 408,851, dated August 13, 1889.

Application filed November 20, 1888. Serial No. 291,365. (No model.)

To all whom it may concern:

Be it known that I, PHILIPP REINER, a resident of Cologne, Rhenish Prussia, Germany, have invented an Improved Chute for Vending Apparatus, &c., of which the following is a specification.

The object of my invention is to provide a coin-chute in which a coin of proper size will pass through said chute to its destination, and in which a coin of different size will pass from said chute without reaching the parts to be operated by the coin.

The invention consists in the novel details of improvement and combinations of parts that will be more fully hereinafter set forth, and pointed out in the claims.

Reference is to be had to the accompanying drawings, forming part of this specification, in which—

20 Figure 1 is a side view of a coin-chute embodying my improvements. Fig. 2 is an end view thereof. Fig. 3 is a side view of said chute looking at the opposite side to that shown in Fig. 1. Fig. 4 is a horizontal section on the line *k k*, Fig. 3. Fig. 5 is a vertical cross-section on the line *cc*, Fig. 3; and Fig. 6 is a sectional view of a modification.

25 In the accompanying drawings, the letters A B represent two rails that are placed side by side, with a space *a* between them, as in Figs. 4 and 5. The upper edges of the rails A B are to be about on a level, the inner edge of the rail B being preferably beveled, as at *b*, for a portion of its length. The width of the space *a* between the rails A B should be slightly wider than the width of the proper coin designed to be passed through this chute.

30 The rails A B may be held adjacent to each other in any suitable manner; but I prefer to secure them at one end by a cross-piece *d* and at their opposite ends by two vertical bars or plates D D. These plates D are placed so that a space *e* will be left between them, which space is just wide enough and high 35 enough to allow a proper-sized coin to pass through, but which prevents larger-sized coins passing between the plates. The space *e* is preferably aligned with the space *a* between the rails A B, as in Fig. 4, so that a coin may 40 pass from the space *e* to the space *a* between the rails A B.

Between the plates D D is a bar *d*², (see Fig. 2,) that extends to the opening *a*, upon which bar a coin rests when passed between the plates D D. The upper ends of the plates 55 D D are secured to a grooved rail E, the groove in said rail being above the space *a* and preferably aligned with the space *e* between the plates D D. The opposite end of the rail E is supported by a post *f*, that extends from the 60 rail A or from the rail B, said post *f* being secured to said upper and lower rails. One side of the rail E is cut away at *g* for a distance adjacent to the groove in said rail, as shown in Fig. 3, whereby the one wall of said groove 65 is left shorter than the opposite wall. I prefer that this cut-away part *g* of the upper rail E shall be on the side opposite the beveled part *b* of the rail B. The object of this cut-away part is to allow a coin or bogus piece of 70 any kind smaller in diameter than the proper coin to easily fall out of the chute on the side of the cut-away portion of the rail E.

Beneath the rail B, and contiguous to its lower side, is placed a movable rail F. This 75 rail F runs parallel to the rail B, and is preferably pivoted at its end opposite the plates D to one of the rails A B, as at *f*², Fig. 4, so that it may swing laterally. The rail F for a portion of its length projects on one side of 80 the rail B to a slight extent across the space *a*. (See Figs. 4 and 5.) This rail should project into said space *a* for such a distance that a proper-sized coin will rest at one edge upon it, and thus be prevented from falling through 85 said space, a portion of the rail A being at one side of said coin above the top of the rail F. This rail F must be so adjusted that a coin of less thickness than a proper coin will slip downward between the rails A and F, 90 and thereby pass from the chute. From a certain point in its length the rail F, if desired, may pass entirely across the space between the rails A B, so as to form a tread *h* for a coin between the rails A B. (See Fig. 2.) 95

The distance from the top of the rail F to the bottom of the groove in the rail E should be such that a proper-sized coin will have free movement at its edges between said rails; but a coin of less diameter will fall sidewise from 100 the grooved rail E, being caused to do so by coming opposite the cut-away part *g* of the

rail E, a coin of greater diameter being kept out by the size of the mouth of the chute.

G is a spring that is secured at one end to a plate D and bears at its free end against the side of the rail F. This spring tends to press the rail F inward to hold it in its proper position, as shown in Fig. 2, the spring G pressing the rail F against a plate D. On an upwardly-extending lug i, carried by the rail F, is a stud or pin j, that passes through the plate D next to the rail F and across the space e between the plates D D, as in Fig. 2. The free end of this stud j, that is within the space e, is beveled, as shown in Fig. 4. As a coin is passed in between the plates D D, the stud j will be moved outward, thereby carrying the rail F away from beneath the space a, and when the coin passes away from said stud the spring G will press the rail F back to its former position, for the purposes hereinafter shown.

II is a short shaft that is hung in bearings l on the under side of the rail F. (See Fig. 1.) At one end the shaft II carries an arm m, that projects upwardly and inwardly over the top of the rail B. This arm m carries at its upper free end a knob or head n, that is beveled or rounded on its inner face, as shown in Fig. 4. The position of this knob or head n is such as to normally turn by its weight the shaft II, so that said knob will extend above the space a between the rails A B. The shaft H, near its opposite end, carries another arm o, that extends partially around the rail A and projects above said rail and about in line with the inner edge of said rail A when the shaft is in its normal position, as clearly shown in Fig. 2.

The arm o is preferably made springy, so that it will throw back a coin which has been pushed into the chute with great force beyond the head n, and will compel it to travel down the rail once more, slowly passing the head n and the arm o by its own gravity.

45 The coin-chute constructed as above shown should be inclined slightly from its end, having the plate D downward toward the free end. This chute may be secured in the desired apparatus in any suitable manner. In 50 the drawings it is shown supported by an upright I, which upright, if used to support the chute, may be secured in the apparatus in any suitable manner. I prefer that the chute be tilted slightly to one side, so that a coin of 55 less than the required diameter will fall from the rail to one side. (See Fig. 2.)

In the modification shown in Fig. 6 the rail B is integral with the rail F. In this case the rails B and F are both movable, the rail B 60 acting as a raised surface on the rail F to prevent a coin slipping off the rail F sidewise.

65 My improved coin-chute operates as follows: When a coin of proper size is passed into the chute between the plates D D, it presses the pin j, and thereby the rail F, to one side, and by the time the coin has passed

said pin the spring G will have pushed the rail F back again under the space a between the rails A B. The coin now rides along between the rails A B and on the rail F, its upper edge passing along the groove in the rail E. When the coin reaches the head n, it presses said head to one side out of its path, thereby moving the free end of the arm o in line with the space a and in the path of and 75 in interference with the rolling coin, thus stopping the coin. As the coin leaves the head n, said head by its own gravity falls back into its original position, and by again turning the shaft II carries the end of the arm o back to its original position out of the path of the coin, thereby giving free passage along the chute for the coin. Bogus pieces of light weight—such as pasteboard, &c.—have not sufficient striking force to push the 80 head n to one side and from across the path of coins. They are therefore stopped by said head and left standing in the chute. When the next coin is passed between the plates D D and strikes the pin j, thereby moving it to 85 one side, and with it the rail F, the piece left on the rails, as above described, will slip down between the rails A and F. If a coin of less than the required thickness is passed into the chute, it will slip down between the rails A and F. 90 On the other hand, a coin of uneven diameter, with its major diameter greater than a proper-sized coin, if passed into the chute, will either stick on its periphery between the rails F and E when its greater diameter 95 comes vertically between said rails or it will move the head n to one side, thereby bringing the end of the rod o over the space a between the rails A B. The distance from the end of the rod o to the nearer edge of the 100 head n being less than the major diameter of such coin, said head will be held to one side, while the rod o will be held in the path of the coin, and the coin thereby be prevented passing down along the rail. When the next coin 105 is passed into the chute, the pin j is again pressed sidewise, carrying the rail F to one side, and thus depriving the former coin, which rested on said rail F, of its support. Said coin will slip downward between the 110 rails A F, and thus be prevented from passing through the chute to the coin-receiving devices in the apparatus. If a coin of less 115 diameter than a proper-sized coin be passed into the chute, it will fall sidewise from said chute when its upper edge comes opposite the cut-away part g of the rail E. The head n also acts to push a coin of small diameter 120 sidewise from the chute.

By making the rail F movable sidewise, and 125 by causing it to be moved by the pin j every time a coin is passed into the chute, any spurious coin, piece of lead, or the like that is passed into the chute and that has been retained in the chute for any of the reasons 130 heretofore mentioned will slip downward between the rails as the rail F is moved, and

thereby be prevented from passing through the chute to the proper place for actuating the selling devices.

This improved coin-chute will be found simple in construction, accurate and efficient in operation, and it takes cognizance of both the difference in diameter and thickness of spurious coins and bogus pieces from that of the proper coins and a difference in weight 10 between the bad and good. It will select the bad from the good by an even or uneven difference in thickness, by an even or uneven difference in diameter, and by a difference in weight if the bogus coin is light.

15 The whole apparatus is arranged so as to prevent permanent clogging of the chute by removing the support from under a retained piece resting in the chute at the time of the entry of another coin.

20 Having now described my invention, what I claim is—

1. In a coin-chute, the rail A, combined with the movable rail F, placed adjacent to the rail A, substantially as described.

25 2. In a coin-chute, the rails A B, placed side by side, combined with the movable rail F, substantially as herein shown and described.

3. In a coin-chute, the rail A, combined with the movable rail F, placed adjacent to the rail 30 A, and with the upper rail E, substantially as described.

35 4. In a coin-chute, the rails A B, placed side by side, combined with the lower movable rail F and with the upper rail E, substantially as described.

40 5. In a coin-chute, the rail A, combined with the movable rail F, placed adjacent to the rail A, and with the grooved upper rail E, having one side cut away, as at g, substantially as described.

45 6. In a coin-chute, the rails A B, placed side by side, combined with the movable rail F and with the grooved upper rail E, having one side cut away, as at g, substantially as described.

7. In a coin-chute, the rail A, combined with the movable rail F, placed adjacent to the rail A, and the pin j, carried by the rail F, substantially as described.

50 8. In a coin-chute, the rails A B, placed side by side, combined with the movable rail F and the pin j, carried by the rail F, substantially as described.

9. The rail A and the plates D D, rising 55 from said rail and having a space between them, said plates acting as a guide for a coin, in combination with the movable rail F, and with the pin j, carried by the rail F and projecting into the space between the plates D D, substantially as described.

10. The rails A B, placed side by side and having a space a between them, and the plates D D, rising from the rails A B and having a space e between them aligned with the space 60 a, in combination with the rail F, and with the pin j, carried by the rail F and project-

ing into the space e, substantially as described.

11. The rail A, and the plates D D, rising from said rail and having a space between them for the passage of a coin, in combination with the movable rail F, placed adjacent to the rail A, and the pin j, carried by the rail F, and with the upper rail E, substantially as described. 75

12. The rails A B, placed side by side and having a space a between them, and the plates D D, rising from the rails A B and having a space e between them aligned with the space a, in combination with the rail E and with 80 the movable rail F, and pin j, carried by the rail F and projecting into the space e, substantially as described.

13. The rails A B, placed side by side and having a space a between them, combined 85 with the movable rail F, projecting partially across the space a for a certain distance and having a tread h at its lower end, substantially as described.

14. The rails A B, placed side by side and 90 having a space between them, combined with a movable rail F and an escapement arranged to operate upon a coin, substantially as and for the purpose set forth.

15. The combination of a rail A and a 95 movable rail F with an escapement arranged to act upon a coin on said rails, substantially as and for the purpose set forth.

16. The rail A and the movable rail F, placed adjacent to the rail A, combined with 100 the shaft H, journaled on the rail F, and with the arm m, carried by the shaft H, and the head n on the arm m, substantially as described.

17. The rails A B, placed side by side and 105 having a space between them, combined with the movable rail F, shaft H, journaled on the rail F, and with the arm m, carried by the shaft H, and the head n on the arm m, substantially as described. 110

18. The rail A and the movable rail F, placed adjacent to the rail A, combined with the shaft H, journaled on the rail F, arm m, having head n, and the arm o, both said arms being carried by the shaft H, substantially 115 as described.

19. The rails A B, placed side by side and having a space between them, combined with the movable rail F, shaft H, journaled on the rail F, arm m, having head n, and the arm o, 120 both said arms being carried by the shaft H, all arranged for operation substantially as herein shown and described.

20. The rail A and plates D D, having a space between them, and the rail E above the 125 rail A, in combination with the movable rail F, pin j, shaft H, having arm m, and head n, substantially as described.

21. The rails A B and plates D D, arranged with the respective spaces a e between them, 130 and the rail E above the rails A B, in combination with the movable rail F, pin j, and

shaft II, having arm m , all arranged and operating substantially as herein shown and described.

22. The rails A B and plates D D, arranged with the spaces $a e$ between them, and the rail E above the rails A B, in combination with the movable rail F, pin j , and shaft II, having arms $m o$, all arranged and operating substantially as herein shown and described.

23. The plates D D, having a space between them, and the rod d^2 and rail E, all arranged to permit the passage of a one-sized coin and to prevent the passage of a larger-sized coin, in combination with the rail A and movable rail F, substantially as described.

24. The rails A B, placed side by side, in combination with the movable rail F and with the spring G, for moving the rail F, substantially as described.

25. The rail A and the movable rail F, placed adjacent to the rail A, combined with the spring G, for moving the rail F, substantially as described.

26. The rails A B, placed side by side, in combination with the movable rail F and with the spring G and the rail E, substantially as described.

27. The rail A and the movable rail F, placed adjacent to the rail A, combined with the spring G and the upper rail E, substantially as described.

PHILIPP REINER.
